(57) **CLAIM**

(22) Filed: **Apr. 9, 2007**

The ornamental design for a multicompartiment receptacle, as shown and described.

DESCRIPTION

FIG. 1 is a perspective view of the multicompartiment receptacle;

FIG. 2 is a front elevational view thereof;

FIG. 3 is a rear elevational view thereof;

FIG. 4 is a right side elevational view thereof, the left side elevational view is not shown as it is a mirror image of the right side view; and

FIG. 5 is a top plan view thereof; and,

FIG. 6 is a bottom plan view thereof.
